CORSET

Gertrude L. Nickerson, Milford, Conn., assignor
to The La Resista Corset Company, Bridgeport,
Conn., a Corporation of Connecticut

Application December 9, 1929. Serial No. 412,788

2 Claims. (Cl. 2—41)

The present invention relates to corsets and particularly an abdominal belt or support for surgical and maternity use, an object of the invention being to provide a garment of this character which will provide proper support without constriction, and which will be hygienic, comfortable, light in weight, and adapted to changes occurring in the condition of the wearer. It is also an object to provide a garment adapted for adjustment to fit individuals having different characteristics, and in which the requirements as to support will vary to a large extent. To this end it is particularly proposed to provide an elastic foundation garment which will conform to the abdomen, and a supporting panel overlying the foundation garment to support the abdomen, and adjustably connected to the foundation garment, so that it may be raised or lowered to provide either high or low support, depending upon the particular requirements and condition of the wearer.

With the above and other objects in view, an embodiment of the invention is shown in the accompanying drawing, and this embodiment will be hereinafter more fully described with reference thereto and the invention will be finally pointed out in the claims.

In the drawing:

Fig. 1 is a perspective view showing the garment 30 as applied to the wearer.

Fig. 2 is a similar view, and showing the supporting panel disconnected and turned back to show the adjustable connection means provided.

Fig. 3 is a front elevation of the foundation 35 garment, the same being flat.

Fig. 4 is a rear elevation thereof.

Fig. 5 is a plan view of the supporting panel.

Similar reference characters indicate corresponding parts throughout the several figures of 40 the drawing.

Referring to the drawing, the corset or abdominal support, according to the present embodiment of the invention, comprises a foundation garment in the nature of an elastic and adjustable abdominal belt, and a substantially non-elastic supporting panel, adjustably connected thereto in overlying relation to the abdominal region in such manner that it may be adjusted to provide either high or low support. The foundation garment consists of a non-elastic back 10 having a central let-out pleat 11, and provided at each side with spaced stays 12 and 13 arranged in slightly diagonal relation, so that they diverge from the upper to the lower ends. The stays have 55 steel or whale-bone inserts 14, secured in the usual

manner. The side or hip portions each consist of a non-elastic section 15 adjacent the outside stays 13, slightly diverging toward the lower end, an elastic yieldable section 16 secured at one edge to the section 15, and a lower elastic yieldable band section 17, secured at its rearward edge to the stay 13 and secured at its upper edge to the lower edges of the sections 15 and 16. The forward edges of the sections 16 and 17 are secured to a vertically disposed eyelet strip 18, having a 60 series of lacing eyelets 19, and adjustably connected by a lacing string 20 to an eyelet strip 21 having eyelets 22. The two eyelet strips are connected at the inner side by a folded let-out pleat section 23.

The eyelet strip 21 at one side is connected to a non-elastic vertical section 24, which in turn is connected to one vertical edge of the elastic yieldable abdominal front section 25, the eyelet strip 21 at the other side being connected to a 75 non-elastic vertical section 26, provided at its inner edge with a series of eyes 27, to which the other vertical edge of the front section 25 is adapted to be secured by a series of hooks 28, as clearly indicated in Fig. 3.

A vertical non-elastic reinforcing strip 29 is secured centrally of the front section and is provided at one point with a snap fastener head 30, to which the abdominal supporting panel section is adapted to be secured in vertically adjust- 85 ed relation, as will hereinafter more fully appear. The lower edge of the front section 25 is curved downwardly and reinforced by elastic strips 31. The construction is such that the section 25 will comfortably conform to the abdomen, and at the same time will not stretch out 90 of shape.

Near the upper end of each of the back stays 13 there is secured a diagonally disposed tape 32 adapted to extend forwardly about the hip sections to adjustably support the ends of the abdominal supporting panel section presently to be more fully referred to. Hose supporters 33 are secured to the lower ends of the stays 13 and the eyelet strips 18.

The abdominal supporting panel 34 is of non-elastic material, except for an elastic gusset insert 35 of triangular form provided centrally in its lower portion. The panel is relatively wide at its central portion and converges toward each end, the upper edge extending downwardly at each side of the center at an inclined angle, and the lower edge extending upwardly at each side of the gusset insert 35 at a somewhat greater inclined angle than the upper edge. A vertical re- 105 110

inforcing strip 36 is secured centrally of the panel, and at its inner side is provided with a series of spaced snap-fastener sockets 37, as clearly shown in Fig. 2, and which are adapted to be secured to 5 the snap-fastener head 30 to vertically adjust the relation of the panel over the front section 25 of the belt. At each end of the panel buckles 38 are secured by tapes 39, and these are adapted to be adjustably engaged by the tape supports 32 to 10 support the panel about the hips from the back section. Hose supporters 40 are secured to the lower edge of the panel at each side of the elastic gusset insert.

In its adjusted position upon the wearer the 15 panel will conform to the abdominal shape and provide a proper and comfortable support without constriction or injurious pressure. The non-elastic nature of the panel and its complete adjustment provides the correct support against 20 prolapsus under any individual condition, and permits the elastic abdominal belt to be worn without excess or misdirected pressure, such as is apt to occur where the elastic belt alone is depended upon for support. The vertical adjustment 25 of the panel provides proper support under widely varying conditions, where the individual need requires either high, low or intermediate support.

Where I have referred to non-elastic material, I preferably employ ordinary woven fabric, as linen, and where I refer to elastic material I preferably employ woven elastic webbing.

I have illustrated and described a preferred 80 and satisfactory embodiment of the invention, but it will be obvious that changes may be made therein, within the spirit and scope thereof, as defined in the appended claims.

Having thus described my invention what I 85 claim and desire to secure by Letters Patent is:—

1. In a maternity corset, a generally non-elastic back section and a generally elastic abdominal section connected thereto and arranged to directly engage the abdomen to provide primary support therefor, a removable and generally non-elastic panel section exteriorly overlying said abdominal section for controlling pressure applied to said abdominal section from the abdomen, and adjustable non-elastic suspension 90 means connected to the non-elastic back section for the panel section.

2. The invention claimed in claim 1, further characterized by means for adjustably connecting 95 said panel section to said abdominal section in a plurality of positions along substantially the entire vertical extent of the abdominal section.

GERTRUDE L. NICKERSON.
